REFUSE CONTAINER OR SIMILAR ARTICLE

Harold G. Karn, Jr., Winchester, Va., assignor to Rubbermaid Commercial Products, Inc.

Filed Nov. 23, 1970, Ser. No. 26,108

Term of patent 14 years

Int. Cl. D7—07

U.S. Cl. D7—194

FIG. 1

FIG. 2

FIG. 3

FIG. 4

FIG. 1 is a perspective view of a refuse container or similar article embodying my new design.

FIG. 2 is a top plan elevation thereof.

FIG. 3 is a partial sectional view on line 3—3 of FIG. 1.

FIG. 4 is a top plan view of the container or similar article with the cover removed.

I claim:

The ornamental design for a refuse container or similar article, as shown and described.
